UNITED STATES PATENT OFFICE.

FRANK M. EDGAR AND ANDREW CHRISTIAN ANDERSEN, OF DETROIT, MICHIGAN, AS-
SIGNOR TO TERNSTEDT MFG. CO., OF DETROIT, MICHIGAN, A CORPORATION OF
MICHIGAN.

ANTIRATTLING DEVICE.

Application filed March 29, 1923. Serial No. 628,404.

To all whom it may concern:

Be it known that we, FRANK M. EDGAR and ANDREW CHRISTIAN ANDERSEN, citizens of the United States, residing at Detroit, in the county of Wayne and State of Michigan, have invented certain new and useful Improvements in Antirattling Devices, of which the following is a specification.

This invention relates to anti-rattlers for door locks, especially anti-rattlers intended to put the outside door handle under yielding torsional strain preventing the same from rattling. It also places the roll-back coupled with the outside handle, under a yielding stress and voids chattering of this member. It is not broadly new to place a retracting lever under spring stress to take up any lost motion to prevent rattling. This is quite a common expedient in vehicle locks. Our improvement consists in applying the spring stress to the outside handle spindle so as to put the handle under yielding stress where it enters the hole of the roll-back to take up any looseness there and also to put the roll-back under stress to prevent the same from chattering against the bolt or against the roll-back stop.

A further improvement is the arrangement of the telescoping cups whereby the spring may be easily and quickly coupled up to the stationary door parts and the turning handle spindle. This will more fully appear in the description following.

In the drawings:

Fig. 1 is a horizontal, fragmentary cross section through the door and door post, showing the handle parts.

Fig. 2 is a fragmentary, sectional view of the lock showing the roll-back, taken on the line 2—2 of Fig. 1.

Fig. 3 is a section on the line 3—3 of Fig. 1.

Fig. 4 is a section on the line 4—4 of Fig. 1.

Fig. 5 is a section on the line 5—5 of Fig. 1.

a designates the usual lock casing in which is slidably guided the bolt b, having an upwardly extending arm c engaged by the roll-back d; into the hub of this roll-back enters the square spindle e of the door handle f. This door handle is formed with a ball g which is locked into the escutcheon

h by spinning down the outer sleeve end i of the hub of the escutcheon. This is only one form of a coupling between the handle and the escutcheon that may be used. There are several other desirable forms of coupling up the escutcheon with the handle so that the handle has the bearing in the escutcheon plate, but still has a limited universal movement in such bearing to permit the escutcheon plate to accommodate itself to the outer surface of the door and to permit the end of the handle spindle to be inserted into the hub of the roll-back of the lock.

Obviously, when the escutcheon is secured to the door by screws, the door handle can be permanently coupled to the roll-back by simply inserting same in the roll-back. However, if the bolt is in any way arrested before its outward limit of projection is reached—it will be clear that the arm c will not engage against the roll-back b. The result will be that this roll-back is free to chatter between the arm c and its stop y. Furthermore, there may be enough clearance between the squared spindle and square opening in the roll-back hub to cause a chattering.

By putting the handle spindle under a yielding torsional stress in either direction, this will take up the lost motion between the handle spindle and the roll-back hub, also between the roll-back and its stop and the bolt arm. This we accomplish by inserting a coil spring in the door handle spindle hole, anchoring one end to the door and the other end to the spindle. However, this anchoring arrangement could not be very easily and quickly done were it not for the special form of fitting that we have designed to accomplish the anchoring to the door and the coupling to the spring.

A pair of telescoping cups are provided; an outer cup s and an inner cup j. The outer cup has a large round central opening t, through which the square spindle e can pass freely. The inner cup which is clamped to the outer telescoping cup by the turned in lugs k of the outer cup, has a squared opening m in the center of the cup. Before these telescoping cups are fitted together, one end of the coil spring x is anchored in the outer cup, the other end is

anchored in the inner cup. The spring is under no strain when the cup is fitted tightly into the counterbore *n*. The counterbore is of such a size that the cup has to be forced 5 into the counterbore and consequently the outer cup becomes anchored by the friction in the door stile.

All that is necessary in assembling the handle is to thread the spindle through the 10 squared opening of the inner cup—or the cup that we may call the rotating cup. The door handle then may be turned as many quarter turns as is necessary to get the desired strength of spring stress. The door 15 handle spindle is then threaded through the square hole in the roll-back and obviously, this roll-back is placed under spring stress, driving it either against its stop *y* or the bolt arm *c*, depending upon which direction 20 the door handle has been turned in putting the coil spring under stress. This will obviously take up not only any looseness between the roll-back and the bolt arm and the roll-back stop, but also any looseness be- 25 tween the spindle and the roll-back hub, making a perfect, anti-rattling device which may be installed in the job as a unit assembly, by simply driving it into the counterbored opening in the door stile or the lock- 30 board.

What we claim is:

1. The combination of a door having a lock board and provided with an opening thereinto, a lock secured on the inside of 35 the door and having a roll-back with a prismatic opening, a door handle provided with a horizontal prismatic spindle passing through said opening and arranged to engage in the prismatic opening of the roll- 40 back, and an anti-rattling device fitted into the opening cut into the door and having

two members relatively rotatable with a spring resistance to such rotation, whereby the handle spindle may be engaged with one of these members and rotated before it is 45 inserted into the opening in the roll-back to thereby put the handle spindle and the roll-back under a yielding stress.

2. The combination of a door lock pro- 50 vided with a roll-back, an outside door han- dle provided with a spindle which can be detachably engaged with the roll-back, and an anti-rattling device threaded onto the spindle and comprising a pair of relatively rotatable members resisted by a spring re- 55 sistance, whereby one of the members can be anchored to the door and the other member to the door handle spindle, and the door handle spindle be turned before it is en- gaged with the roll-back for the purpose of 60 putting the roll-back and handle under yielding stress.

3. The combination of a lock with a roll- 65 back, an outside door handle provided with a spindle arranged to be detachably engaged with the roll-back, an anti-rattling device comprising a pair of telescoping cups, one rotatable within the other against the re- sistance of a spring, whereby the outside 70 cup may be fitted into the mortise of the door to anchor one end of the spring and the other cup may be threaded non-rotatably onto the door handle spindle to permit the spindle to be turned before the spindle is threaded into the hole in the roll-back, there- 75 by to place both the roll-back and the spindle under yielding stress.

In testimony whereof we affix our signatures.

ANDREW CHRISTIAN ANDERSEN.
FRANK M. EDGAR.
